INDIVIDUALLY MATCHED BEAD SUPPORTS
FOR COAXIAL CABLES

Ernst Weber, Mount Vernon, and John W. E. Griemsman, Bellaire, N. Y., assignors to Polytechnic Institute of Brooklyn, Brooklyn, N. Y., a corporation of New York

Application January 2, 1947, Serial No. 719,808

1 Claim. (Cl. 178—44)

1

This invention relates to bead supports for coaxial cables, and it is especially concerned with the design of such supports to provide the individual matching of each bead with the cable to reduce or prevent wave reflection.

Heretofore, reflection in bead supported coaxial cables has been reduced or eliminated in two principal ways. First, the beads have been arranged in spaced pairs whereby reflection from one bead is cancelled by reflection from the other bead. Secondly, individual beads have been compensated by undercutting or overcutting the adjacent conductors, but this has been done simply by taking into account the nominal impedance of the bead, and without taking into consideration the capacitance introduced by the sharp corners of the cuts which are formed in the metallic conductors.

The simplified design principles discussed above are stated in Sperry's book on "Microwave Transmission Design Data," pages 46 to 53.

There are certain deficiencies in the prior methods of obtaining reflectionless transmission. First, the spaced pairs are frequency sensitive depending upon the thickness of the beads used, and neglect of the thickness results in a VSWR beyond that expected from the compensation. Also, it has been found that undercut or overcut beads which were designed without regard to the capacitance resulting from the sharp corners did not perform as expected, especially in the high frequency ranges of 3000 megacycles per second and above.

The present invention provides a bead structure which is individually matched to the characteristic impedance of the cable so as to take into consideration the capacity introduced by the sharp corners of the undercutting or overcutting. This results in much lower VSWR in the high frequency ranges, and also produces a broadband characteristic. Furthermore, the bead supports of the present invention are individually compensated or matched, and pairing of the beads is not necessary.

The present invention will be explained in connection with the accompanying drawing in which

Figures 1, 2 and 3 are longitudinal sectional views of coaxial cables showing, respectively, an undercut and overcut thin bead support, a "spool" type of bead, and an overcut "quarter-wave" type of bead.

Figures 1a, 2a and 3a are the equivalent two-conductor transmission lines of Figures 1 to 3.

Figure 4 is an admittance diagram used in explaining the invention.

2

Figure 5 is a graph showing two curves or plots used in designing the bead supports of the present invention.

In each of Figures 1 to 3, the outer conductor 5 and the bead 2 are shown in section, while the center conductor 3 is shown in elevation.

It can be shown that any discontinuity in the coaxial cable having axial symmetry may be represented by a lumped capacity at the place of discontinuity. Thus in each of Figures 1a, 2a and 3a lumped capacity elements C are shown at each point of discontinuity in Figures 1, 2 and 3 respectively.

The electrical performance characteristics of 15 the beads shown in Figures 1 to 3 are shown by means of the admittance diagram of Figure 4 giving the admittance loci of the three bead types.

Consider first the simplest case of the so-called "quarter wavelength" bead of Figure 3. Looking at the two wire equivalent in Figure 3a, the discontinuities are represented by capacitances C, C connected in shunt on the transmission line. A condenser in the chart of Figure 4 is represented by a vertical line (susceptance plus $j\omega C$). With such a diagram, a connection in shunt means merely a vertical addition to the input admittance of the coaxial line behind the bead (load end). Thus, for a matched line behind the bead, 20 with input admittance equal to the characteristic admittance Y_0 , one starts with that value in the diagram and adds it to the susceptance $j\omega C$. This leads to the point (a) in the chart, as the total input admittance of the two-wire line at 25 the point (a). To obtain the locus of the input admittances proceed in a clockwise direction around the circle about Y_0 . A point (b) in this circle may be found which is directly under Y_0 . By symmetry the addition of the susceptance due to the discontinuity at the front of the bead will 30 carry us back to Y_0 resulting in a "match." If this procedure is followed on an exact transmission line chart the arc (ab) will be less than a quarter wavelength in the dielectric for exact cancellation at one frequency. At neighboring 35 frequencies, the needed length or width of the dielectric bead will differ slightly and satisfactory performance extends over a rather broad wavelength range. The final width of the bead may be calculated exactly for mid-band wavelength 40 using transmission line equations given herein-after.

In the second case, that of the "spool" bead of 45 Figure 2, the procedure is initially the same. At some point (c) in the bead as shown in both 50 diagrams the bead is reduced in diameter. This

lowers the characteristic admittance to the value Y_b' which is lower than the characteristic admittance Y_0 of the line. This results in an increase in the characteristic impedance (the reciprocal of characteristic admittance) of the bead section over and above the normal characteristic impedance of the line. Actually there is some field distortion occurring at place where the vertical cut in the bead appears and some capacitance. This capacitance however is known to be quite small and is neglected for this case. Proceed now about Y_b' to the point (d), the place where the bead diameter returns to that of the normal characteristics admittance Y_0 . Proceed about Y_0 to (b) and return to Y_0 by way of the susceptance at the bead face.

In Figure 1, for the thin bead we proceed in the same manner as for the quarter-wave bead except that the input admittance locus is now in a circle about Y_b instead of Y_0 . With this procedure a much smaller portion of the circle is required.

To test for the relative frequency sensitivity of the beads we note that the effect of the capacitance measured in susceptance is given by ωC (see Figure 4), a quantity proportional to frequency. But the length of circular path between (a) and (b) is also proportional to frequency. When the frequency is changed we note that the path length for the thin bead most nearly approaches the length $2\omega C$. Thus for the lengths varying together this thin bead gives the best approximation to the design condition when the frequency is varied.

From the electrical point of view of broad bandness the bead given in Figure 1 is the best. That of Figure 2 is next best and that of Figure 3 is the worst. The bead of Figure 3 depends least upon the exact evaluation of the capacitance at its face.

The design principles underlying the present invention will now be discussed under two headings, that is, the general bead formula will be developed first and then the formula for thin beads.

I. The general bead formula

Consider a coaxial line bead structure which has a different diameter ratio than that of the coaxial line in which the bead is to be used as a support. The bead may fit into only an overcut space, only an undercut space, or, as shown in Figure 1, in both an overcut and undercut space. The equivalent two-wire transmission line representation of Figure 1 is given in Figure 1a. In Figure 1, D and d are, respectively, the outer and inner diameter of the air coaxial line itself. The characteristic admittance is then given by

$$Y_0 = \frac{1}{60 L_n \frac{D}{d}} = \frac{1}{Z_0} \quad (1)$$

The outer and inner diameters of the bead are, respectively, D' and d' , such that the characteristic admittance of the bead section is given by

$$Y' = \frac{\sqrt{\epsilon}}{60 L_n \frac{D'}{d'}} = \sqrt{\epsilon} Y_{is} \quad (2)$$

where ϵ is the dielectric constant of the bead material and Y_{is} may be called a geometric characteristic admittance. For the configuration shown above, most of the field distortion occurs in the dielectric. In this case the capacity, C ,

caused by this distortion, may be either calculated or measured and may be represented as

$$C = \epsilon \cdot C_g \quad (3)$$

5 where C_g is a geometric capacity resulting from the geometric distortion alone and would thus be related to Y_{is} . (See "Equivalent Circuits for Discontinuities in Transmission Lines" J. R. Whinnery and H. W. Jamieson, Proc. I. R. E., 32, 98-114 February 1944.) If the bead becomes thin, the capacities which are assigned to each face become smaller because of the interaction of the distortion fields. These effects can only be approximately calculated.

10 15 There are a large number of combinations of values of the diameter ratio

$$\frac{D'}{d'}$$

20 the thickness of the bead, l , and the dielectric constant, ϵ , for which matched beads result. A general formula illustrating this fact can readily be derived. In order that the bead be matched, the input admittance to the bead which is terminated in Y_0 should have an input admittance equal to Y_0 . Analytically this is written

$$Y_0 = Y_{in} = j\omega C + \frac{1 + \frac{Y_0 + j\omega C - Y'}{\epsilon^{-2i\beta l}}}{1 - \frac{Y_0 + j\omega C - Y'}{\epsilon^{-2i\beta l}}} \quad (4)$$

30 where e is the base of natural logarithms. This can be reduced to the formula

$$\tan \beta l = \frac{\frac{2\omega C}{Y'}}{\left(\frac{Y_0}{Y'}\right)^2 + \left(\frac{\omega C}{Y'}\right)^2 - 1} \quad (5)$$

40 where Y_0 , Y' , and C are defined above and

$$\beta = \frac{2\pi}{\lambda \alpha} = \sqrt{\epsilon} \frac{2\pi}{\lambda_0} \quad (6)$$

If the diameter ratio

$$\frac{D'}{d'}$$

45 is arranged to give a bead whose characteristic impedance is equal to that of the air coaxial line, then $Y' = Y_0$. For this Equation 5 reduces to

$$\tan\left(\sqrt{\epsilon} \frac{2\pi l}{\lambda_0}\right) = \frac{1}{\frac{\omega C}{2Y_0}} \quad (7)$$

50 55 As a rule,

$$\frac{\omega C}{2Y_0} \ll 1$$

60 and the equation then specifies that

$$\frac{2\pi}{\lambda \alpha} = \sqrt{\epsilon} \cdot \frac{2\pi l}{\lambda_0} \approx (2n+1) \frac{\pi}{2}$$

65 where $n = 0, 1, 2, 3$, etc. that is, the bead shall be an odd multiple of a $1/4$ wavelength in the dielectric. A more exact formula for the length is given by Equation 7.

70 Using Equations 2 and 3 in 5, a relationship is obtained which clarifies the interrelationship of various factors

$$\tan\left(\sqrt{\epsilon} \frac{2\pi l}{\lambda_0}\right) = \frac{2 \left(\frac{\omega C_s}{Y_{is}}\right) \sqrt{\epsilon}}{\left(\frac{Y_0}{Y_{is}}\right)^2 + \epsilon \left(\frac{\omega C_s}{Y_{is}}\right)^2 - 1} \quad (5')$$

II. Thin bead formula

Special advantages result from the use of thin beads designed such that the conditions contained in Equation 5 are obeyed. If, in such a bead, broadband properties are achieved at some ultra high frequency, the bead should be nearly reflectionless down to D. C. The thin bead is defined as the type for which it may be assumed that

$$\tan \left(\sqrt{\epsilon} \cdot \frac{2\pi l}{\lambda} \right) \approx \sqrt{\epsilon} \cdot \frac{2\pi l}{\lambda_0}$$

that is, approximately for the arguments of 10° or less. Further,

$$\begin{aligned} \omega C_s &= \frac{2\pi Vl}{\lambda_0} \cdot C_s = \frac{2\pi}{\lambda_0} \cdot C_s \cdot \frac{1}{\sqrt{L_0 C_0}} \cdot \frac{Y_0}{\sqrt{L_0}} \\ &= \frac{2\pi}{\lambda_0} \frac{C_s}{C_0} Y_0 \end{aligned}$$

where C_0 is the capacitance per unit length, L_0 is the inductance per unit length and V_0 is the velocity of propagation in free space. Substituting these values in 5 yields

$$l = \frac{2 \frac{C_s}{C_0} \frac{Y_0}{Y_{is}}}{\left(\frac{Y_0}{Y_{is}} \right)^2 \frac{1}{\epsilon} - 1} \quad (5'')$$

for

$$\left(\frac{\omega C_s}{Y_{is}} \right)^2 \ll \left(\frac{Y_0}{Y_{is}} \right)^2$$

which is usually the case. Simplifying, one has

$$l = \frac{2 \frac{\epsilon C_s}{C_0} \left(\frac{Y_0}{Y_{is}} \right)}{\left(\frac{Y_0}{Y_{is}} \right)^2 - \epsilon} \quad (5''')$$

It is noted that for the approximations made, the match condition (5''') is independent of frequency. As the frequency becomes smaller the approximation becomes better. If an attempt is made to go higher in frequency, however, the approximation is gradually invalidated and other means, such as spacing, may be applied to reach satisfactory matching conditions.

The degree of the approximation determines the frequency sensitivity of the bead and to this extent governs the mechanical thickness that can be used for a given frequency. In order to reach higher frequencies, the dielectric constant of the bead should be made as small as possible. An attempt should be made to always attain maximum thickness which permits the assumption of mechanical strength at the higher frequencies is desired.

Design procedure for thin beads

The design procedure for thin beads according to the present invention will now be explained in a number of steps. The calculated values of capacity cannot be ascertained with sufficient accuracy to give the final specifications for the bead structure, but the theoretically predicted bead performance can be realized by making a few final check measurements, as will be explained later.

Step 1.—For a given bead material, a bead thickness, l , should be chosen that is short compared to the shortest wavelength (highest frequency), at which the bead is expected to be used.

Specifically, this length is specified by the statement

$$l \leq \frac{\lambda_{dm}}{36}$$

where λ_{dm} is the wavelength in the dielectric corresponding to the highest frequency. If this condition for the length or thickness is met, Equation 5''' assures that the desired electrical properties can be attained for all longer wavelengths. It is permissible to exceed this thickness if a certain amount of reflection is not objectionable. In some microwave applications the thickness may be as much as $\frac{1}{16}$ of the wavelength in the dielectric corresponding to the highest frequency.

Step 2.—With the length of bead and the dielectric constant of the bead material chosen as above, it is now possible to plot the value of

$$\left(\frac{C_s}{C_0} \right)$$

as a function of

$$\left(\frac{Y_0}{Y_{is}} \right)$$

by utilizing the relationship between these quantities given by Equation 5'''. The values of Y_0 and C_0 are constants known from the dimensions of the standard coaxial line for which the bead is to be used. This curve then gives the corresponding values of

$$\left(\frac{C_s}{C_0} \right)$$

and

$$\left(\frac{Y_0}{Y_{is}} \right)$$

for which the bead is will be matched. Curve 4 of Figure 5 shows these values for a specific example given hereinafter.

Step 3.—For a given proportioning of the overcutting and undercutting as discussed in section I above, and for a given bead thickness, l , the capacity, C_s , may be calculated as a function of Y_{is} . By this means an independent plot of

$$\left(\frac{C_s}{C_0} \right)$$

as a function of

$$\left(\frac{Y_0}{Y_{is}} \right)$$

may be obtained. This curve, one example of which is shown at 5 in Figure 5, now represents the actual

$$\left(\frac{C_s}{C_0} \right)$$

as calculated from the ratio

$$\left(\frac{Y_0}{Y_{is}} \right)$$

There are certain practical limits on the amount of overcutting and undercutting. Where possible, the inner conductor should be undercut to the maximum amount which is permitted by mechanical strength considerations of the line. Ordinarily, the diameter of the undercut should not be less than approximately $\frac{1}{8}$ the diameter of the inner conductor itself. The amount of overcutting, if required, is then determined by the design formula given above. Where undercutting of the inner conductor is not permitted, it is necessary merely to determine the amount of overcut.

Step 4.—It will be found that the two curves plotted in Steps 2 and 3 will intersect at a certain point, and at this point the condition for match is satisfied, that is Equation 5''' is satisfied by the capacity C_g as calculated from the dimensions. Also, the resultant value Y_{ig} gives reasonable dimensions which can be used for design purposes.

Step 5.—Since the capacity values, C_g , will not be quite accurate, but generally can be given within limits not exceeding $\pm 15\%$, the final reflectionless bead must be obtained by testing a series of beads having thickness varying $\pm 15\%$ from the thickness originally chosen. A series of 3 or 4 beads, however, should be sufficient to obtain the condition stipulated by Equation 5'''. At the higher frequencies, making the bead 15% thicker may cause violation of the condition of Step 1. This is not serious in general, since the departure from operation stipulated by Equation 5''' occurs only at a slow rate as the condition is violated.

The above method of design may be used for other non-characteristic impedance beads by using the exact Equation 5 in the place of (5'''). The electrical performance of these beads, however, will be limited to given bands of frequency and do not look as promising electrically as the thin bead.

The curves shown in Figure 5 are for an over-cut thin bead of the type shown in Figure 3 in which the inner diameter of the outer conductor is 0.8125 inch and the diameter of the inner conductor is 0.375 inch. The bead is formed of polystyrene having a dielectric constant of 2.56, a thickness of 0.178 inch and an outside diameter of 1.5 inches. The crossover point of the curves 4 and 5 occurs at 1.793 of the ratio Y_0/Y_{ig} .

We claim:

A coaxial cable in which the center conductor

is supported by a thin dielectric bead positioned in an annular groove formed in at least one of the conductors of said cable with the mismatch caused by the additional capacitative reactance introduced by the corners of said groove being substantially eliminated by an increase of the characteristic impedance, $Z_{ig}=1/\sqrt{\epsilon} Y_{ig}$, of the bead section over the normal characteristic impedance $Z_0=1/Y_0$ of the adjoining transmission line, according to the formula

$$l = \frac{2 \frac{\epsilon C_g}{C_0} \cdot \left(\frac{Y_0}{Y_{ig}} \right)}{\left(\frac{Y_0}{Y_{ig}} \right)^2 - \epsilon}$$

wherein l is the length of the part having the characteristic impedance Z_{ig} , ϵ is the dielectric constant of the bead section, C_g the effective additional capacitance introduced by the groove and C_0 is the normal capacitance per unit length for the standard transmission line of characteristic impedance Z_0 .
